This invention relates to circuit breakers for alternating current where the electrodes are mounted in a highly evacuated envelope.

In such circuit breakers, separation of the electrodes leads to the formation between their contact surfaces of a small number of bridges of molten electrode metal which explode as the separation proceeds and leave corresponding arcs.

When the separation starts just after a current zero, the bridges are quite small and their explosion therefore does little damage to the contact surfaces. The cathode spots of the arcs which are left by these bridges are found to multiply quickly and spread out more or less uniformly over the contact surfaces so that arcs become distributed over these surfaces. These surfaces are always made sufficiently large to ensure that the current density at them when the following current maximum is reached is insufficient to cause general overheating of the surfaces.

If the separation of the electrodes is started at a later epoch of the current cycle up to the current maximum, the bridges formed become larger in size, and greater damage is therefore done to the contact surfaces when these bridges explode. The corresponding arcs left after this explosion of course then have to carry larger instantaneous currents, and the cathode spots of these arcs, instead of spreading out over the contact surfaces, remain concentrated on the molten patches which were left on the contact surfaces at the places formerly occupied by the bridges. There is some evidence to show that this concentration of cathode spots takes place when the instantaneous current is greater than a somewhat ill-defined value (which is of the order of 10,000 amperes for copper electrodes). This concentration of the cathode spots and thus of the arcs, which it will be noted takes place no matter how large the contact surfaces are made, keeps the temperature of the molten patches high so that these remain overheated. Such overheating leads, in the case of copper electrodes, to these patches remaining in the molten state, with consequent increased damage, while in the case of all the metals commonly employed in manufacturing electrodes (i.e. copper, steel and tungsten) the resultant high vapor pressure exerted by the electrode metal in the gap between contact surfaces often causes re-ignition of the arcs after the next current zero when the re-striking voltage is applied.

According to the present invention, three or more pairs of cooperating electrodes are provided, including a main pair and two or more auxiliary pairs which are of lower arcing voltage than the main pair and which are each connected electrically in parallel with the main pair, and the operating mechanism of the circuit breaker is designed so that during the breaking operation it first separates only the cooperating electrodes of the auxiliary pairs, so that in operation to interrupt a current, bridges of electrode metal first form and then explode between cooperating electrodes, and then the mechanism separates the electrodes of the main pair, the arrangement of the electrodes

2

being such that an arc at the main pair or an arc at any one of the auxiliary pairs can cause the formation of arcs at all the auxiliary pairs. The pair of electrodes of higher arcing voltage are referred to as the main pair merely for convenience rather than to indicate their size or conductive capacity relative to the auxiliary pairs. Again for convenience the electrodes of the main pair, their contact surfaces and any arc formed between them are referred to as main electrodes, main contact surfaces and a main arc respectively, whilst the word "auxiliary" is employed for corresponding terms referring to the auxiliary pairs.

In a circuit breaker constructed according to this invention, the bridges formed between cooperating auxiliary contact surfaces are smaller than corresponding bridges found in known circuit breakers which have but one pair of electrodes, and the auxiliary arcs have a smaller current than corresponding arcs found in such circuit breakers. There are two reasons for this. First of all, some 15 of the current is diverted through the main electrodes, which are of course still in contact. It will be realized that an immediate and complete diversion is not possible owing to the finite inductance of the auxiliary pairs. The second reason is that the current which is not diverted divides 20 between the different auxiliary pairs. This division of current is surprising and investigation has shown that this division is due to the previously unknown fact that the voltage-current relationship for arcs in a vacuum is positive so that an increase in the current passing through 25 an arc leads to an increase in the voltage across it. It is well known that arcs in air have, on the contrary, a negative voltage-current relationship and that if, therefore, an airbreak type of circuit breaker were provided with more than one pair of cooperating electrodes, an arc 30 would be maintained at only one of them on their separation.

Thus in a breaker according to the invention the bridges are smaller than in known breakers having one pair of electrodes and dealing with the same current, and the 35 damage to the contact surfaces is correspondingly smaller. At the same time, the currents which can be handled without concentration of arcs and consequent overheating taking place is larger.

When the bridges between cooperating auxiliary contact surfaces have exploded, the main electrodes are separated. The main arc then formed does, of course, cause a certain amount of damage at the main contact surfaces, but this does not matter owing to the continued good condition of the auxiliary contact surfaces. This main arc 45 very quickly dies out because any auxiliary arc in existence grows at its expense owing to the different arcing voltages of the main and auxiliary pairs, while if the auxiliary arcs have themselves died out before the main electrodes are separated, such arcs are started again by the arc-initiating energy (which may be metal vapor or electrons or radiation) which is emitted from the cathode spots of the main arc and which is travelling towards an auxiliary contact surface (on arriving, this energy initiates cathode spots). It will be realized that if the 50 main electrodes were separated before the bridges between cooperating auxiliary contact surfaces exploded, and if this separation took place at a moment when a large instantaneous current was flowing through the breaker, the diversion of current back again from the main pair to the auxiliary pairs would lead to an increase in the size of the bridges, with consequent increased damage on their subsequent explosion.

In the final stage of the current interrupting operation, the auxiliary arcs themselves are extinguished at a current zero.

When the current interrupting operation is started near

a current zero, it sometimes happens that only one auxiliary arc forms (this may be the result of slight differences in the construction of the auxiliary electrodes) so that if no other auxiliary arc were started the current at the particular auxiliary pair concerned would be several times greater than usual, with consequent increased damage. In a breaker according to the invention, other auxiliary arcs are started due to the arrangement of the auxiliary electrodes, which is such that when an arc is formed at any one of the auxiliary pairs, the arc-initiating energy emitted passes towards at least one of the other auxiliary pairs and starts there an arc, which then emits energy to start a further arc, and so on until there are arcs at all the auxiliary pairs.

In a preferred form of construction, shields which remain relatively cool during current interrupting operations of the breaker are arranged and shaped so as to intercept and adsorb a major proportion of all arc-initiating energy emitted on arcing, which is not travelling towards a contact surface of any auxiliary electrode. This adsorption reduces the amount of energy travelling into regions of the envelope other than those in the neighbourhood of the contact surfaces, and thus reduces the risk of re-ignition after a current zero over long paths in the first-mentioned regions.

In order that the invention may be more easily understood and readily carried into effect, a circuit breaker constructed according to it and capable of handling 15,000 R.M.S. amperes, together with a modified form of construction, will now be described with reference to the accompanying drawings in which:

Figure 1 is an elevation, partly in section, of the circuit breaker;

Figure 2 is a cross-section taken along the line II—II of Figure 1;

Figure 3 is an elevation similar to Figure 1 but showing the modified form of construction; and

Figure 4 is a cross-section similar to Figure 2 but taken along the line IV—IV of Figure 3.

Referring first of all to Figures 1 and 2, the circuit breaker includes two main, vertically disposed cooperating electrodes 1a and 1b, made of tungsten and of one inch diameter, and fourteen auxiliary, vertically disposed copper electrodes of half inch diameter and with hemispherical ends, the eight upper ones being indicated at 2a and the six lower ones at 2b. As is best seen in Figure 2, the electrodes 2a and 2b are arranged symmetrically in a ring around the main electrodes 1a and 1b, and the arrangement is such that the rings of upper and lower electrodes 2a and 2b interfit with one another so that each of the six lower electrodes 2b engages its two nearest neighbours. By this arrangement, the fourteen electrodes cooperate with each other at twelve places and so produce twelve auxiliary pairs.

The main electrode 1b is mounted on a copper stem 3 to which one of the conductors for alternating current, indicated at 4, is secured by nuts 5. The stem 3 is connected through an insulating sleeve 6 to a mechanism (not shown) for moving the stem 3 up and down to operate the breaker. This stem 3 not only carries the main electrode 1b but also a conducting disc 8 on which all the electrodes 2b are mounted, being secured in position by nuts 9.

The upper auxiliary electrodes 2a are all screwed into a fixed conducting hanger 15 so that these electrodes 2a are immovable. The upper main electrode 1a is, on the other hand, secured to a copper stem 16 which is vertically movable. This stem 16 passes upwards through an opening in the hanger 15 and an opening in a conducting disc 17 secured to the hanger 15, and at its top end the stem 16 carries nuts 18 holding in position the other conductor for alternating current indicated at 19. A spring 20 presses downwardly on these nuts 18 to keep the main electrodes 1a and 1b in engagement. Conducting braids 21 connect the stem 16 to the annulus 17

so that each auxiliary pair of electrodes 2a and 2b are electrically in parallel with main pair 1a and 1b.

When the sleeve 6 is moved downwardly from the position shown in Figure 1, the auxiliary electrodes 2a and 2b separate and, in general, bridges form and explode between the electrodes of each auxiliary pair and auxiliary arcs then form. The main electrodes 1a and 1b, however, do not separate during this initial stage of the breaking operation, since the upper main electrode 1a is moved downwardly by the spring 20 and keeps in engagement with the electrode 1b. During this downward movement of the electrode 1a a collar 30 secured to the stem 16 engages a fixed stop 31 so that the electrode 1a comes to an abrupt halt when the contact surfaces of the electrodes of each auxiliary pair are separated by about 5 mm. Separation of the main electrodes 1a and 1b then follows, with the formation of the main arc.

The formation and extinction of the main and auxiliary arcs have already been described in detail and need only be referred to briefly here. The auxiliary arcs, formed during the initial stage of the current interrupting operation, have a low current for reasons already mentioned so that major damage of the auxiliary electrodes

25 2a and 2b is avoided. When the main arc forms at the tungsten electrodes 1a and 1b on their separation, this arc is able to cause auxiliary arcs to form at the auxiliary copper pairs 2a and 2b, because of the low arcing voltage of copper compared with tungsten. It can be seen that in order to permit this formation, the contact surfaces of all the electrodes are arranged at about the same level, so that arc-initiating energy emitted by the main arc is able to reach the auxiliary contact surfaces so as to start auxiliary arcs, if these do not already exist. 35 It should be noted that the lower auxiliary contacts 2b remain fixed with main contact 1b at all times and the upper ends of the auxiliary contacts 2b intersect the common plane of the contacting faces of the main contacts 1a and 1b, so that when the main contacts open, arc-initiating energy travels outwardly in this common plane and strikes the contact surfaces of auxiliary contacts 2b. By properly selecting the amount of overlap between auxiliary contacts 2a and 2b, and by properly positioning the collar 30 with respect to the fixed stop 31, the lower 40 ends of the upper auxiliary contacts 2b may also intersect the common surface-contacting plane of the main electrodes at the time of opening of the main electrodes. This arrangement of the contact surfaces also ensures that energy from an arc at any auxiliary pair is able to reach 45 the auxiliary contact surfaces of other auxiliary pairs to start arcs there, if these do not already exist.

Two shields in the form of inner and outer coaxial cylinders 35 and 36 are arranged so that the inner cylinder 35 surrounds only the main pair 1a and 1b, whilst 55 the outer cylinder 36 surrounds all the pairs. In order to permit the formation of arcs at all the auxiliary pairs by an arc at the main pair, the inner cylinder 35 is formed with a large number of openings 38 to allow the passage of energy from the arc at the main pair to the 60 contact surfaces of each of the auxiliary pairs. It will be clear that passage of energy from any auxiliary electrode to adjacent ones is not interfered with at all by the cylinders 35 and 36.

The function of these cylinders 35 and 36, which remain cool relatively to the regions of arcing during operations of the circuit breaker, is to intercept and adsorb energy which is emitted on arcing and which is not travelling towards a contact surface of any auxiliary electrode. This adsorption of energy prevents its escape 70 from the regions in the neighbourhood of the contact surfaces and thus reduces the risk of re-ignition over long paths in the envelope after a current zero. The cylinders are arranged as close to the electrodes as is 75 possible consistent with the electrical strength required

of the breaker, and they also extend a substantial distance along each electrode.

The inner sleeve 35 is held in position within the outer sleeve 36 by metal spacing bars 40, while the outer cylinder 36 is held in position in the envelope of the circuit breaker by further metal bars 41. The envelope itself consists of a metal cylinder 42, to which the bars 41 are brazed, a glass cylinder 43 secured to the upper end of the cylinder 42, a metal end fitting 44 secured to the cylinder 43 and brazed onto the hanger 15, a further glass cylinder 45 secured to the lower end of the cylinder 42, a further metal cylinder 46 secured to the cylinder 45, an end fitting 48 and a box-like structure 49 similar to the hanger 15 and annulus 17. Metal bellows 50 and 51 are provided within the hanger 15 and the structure 49 respectively to complete the envelope, and to allow the movements of the various electrodes to take place. A tube 52 is provided in the structure 49 to enable the envelope to be exhausted, this tube 52 being sealed off after rigorous de-gassing of the envelope and its contents, and when the pressure is of the order of 10^{-6} to 10^{-7} mm. of mercury.

In the form of construction shown in Figures 3 and 4, only ten auxiliary electrodes are provided and these are arranged, in completely separate pairs, in a ring around the main electrodes. Each of these pairs of auxiliary electrodes is surrounded by separate cylinders 55 which are held in position by metal bars 56 secured to the metal cylinder 42. These cylinders 55 perform the same functions as the cylinders 35 and 36 shown in Figures 1 and 2, and in order to permit the passage of energy to all the auxiliary pairs, these cylinders are formed with openings indicated at 57.

In a modification (not shown) of the form of construction shown in Figures 1 and 2, each auxiliary electrode engages its two nearest neighbours after a making operation.

I claim:

1. A circuit breaker for alternating current comprising a highly evacuated envelope, a main pair of cooperating metallic electrodes mounted in said envelope, at least two auxiliary pairs of cooperating metallic electrodes mounted in said envelope in laterally spaced relation with respect to each other and with respect to said main electrodes, said auxiliary electrodes being formed of a metal of lower arcing voltage than said main electrodes and each of said auxiliary pairs being connected electrically in parallel with said main pair, and means for operating said breaker, said means acting during the breaking operation first to separate only the cooperating electrodes of the said auxiliary pairs, whereby in operation to interrupt a current, bridges of electrode metal form and then explode between said cooperating electrodes of said auxiliary pairs, and said means then acting to separate the electrodes of said main pair, the electrodes of the said main and said auxiliary pairs being such that an arc at the said main pair causes the formation of arcs at all the auxiliary pairs and such that

an arc at any one of the auxiliary pairs causes the formation of arcs at all the auxiliary pairs the engaging surfaces of the main electrodes as they are about to separate, being in a common plane passing through a contact surface of at least one electrode of each of said auxiliary pairs of electrodes, whereby an arc at the main pair produces arc-initiating energy which travels in said plane and causes formation of arcs at all said auxiliary pairs.

an arc at any one of the auxiliary pairs causes the formation of arcs at all the auxiliary pairs the engaging surfaces of the main electrodes as they are about to separate, being in a common plane passing through a contact surface of at least one electrode of each of said auxiliary pairs of electrodes, whereby an arc at the main pair produces arc-initiating energy which travels in said plane and causes formation of arcs at all said auxiliary pairs.
